US0D1054368S

(12) **United States Design Patent** (10) **Patent No.:** **US D1,054,368 S**
(45) **Date of Patent:** **** Dec. 17, 2024**

(54) **MOBILE POWER SUPPLY**

(71) Applicant: **Dongguan Weilaian New Energy Technology Co., Ltd.**, Guangdong (CN)

(72) Inventor: **Wang Liming**, Guangdong (CN)

(73) Assignee: **Dongguan Weilaian New Energy Technology Co., Ltd.**, Guangdong (CN)

(**) Term: **15 Years**

(21) Appl. No.: **29/900,131**

(22) Filed: **Aug. 17, 2023**

(30) **Foreign Application Priority Data**

May 31, 2023 (CN) 202330331238.2

(57) **CLAIM**

The ornamental design for a mobile power supply as shown and described.

DESCRIPTION

FIG. 1 is a front, right and top perspective view of a mobile power supply, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1; and,

FIG. 11 is an enlarged view of detail 11 in FIG. 2.

The broken lines depict portions of the mobile power supply that form no part of the claimed design.

The dot-dash broken lines in FIGS. 1, 2, 9, 10 and 11 depict the boundaries of the enlargements that form no part of the claimed design.

1 Claim, 11 Drawing Sheets
